G. R. RICH.

PISTON.

APPLICATION FILED SEPT. 30, 1915.

1,185,825.

Patented June 6, 1916.

Inventor:
George R. Rich,
by Charles O. Shervey,
his Atty.

UNITED STATES PATENT OFFICE.

GEORGE ROBERT RICH, OF OAK PARK, ILLINOIS, ASSIGNOR TO RICH TOOL COMPANY,
OF CHICAGO, ILLINOIS, A CORPORATION OF ILLINOIS.

PISTON.

1,185,825.

Specification of Letters Patent. Patented June 6, 1916.

Application filed September 30, 1915. Serial No. 53,452.

To all whom it may concern:

Be it known that I, GEORGE R. RICH, a citizen of the United States, and a resident of Oak Park, county of Cook, and State of Illinois, have invented certain new and useful Improvements in Pistons, of which the following is declared to be a full, clear, and exact description.

This invention relates to pistons for internal combustion engines, and is in the nature of an improvement upon the piston which forms the subject matter of an application for Letters Patent filed by me in the United States Patent Office on the 15th day of May A. D. 1915, and designated by the Serial No. 28256.

The primary object of the present invention is to provide a piston (having the usual wrist pin connection with its connecting rod), with an independently expansible head portion, whereby the main objects of my prior invention in pistons may be attained, and whereby certain additional and improved features are made possible.

Other objects are to simplify the construction thereof; to render assemblage of the parts more easy; and to provide a piston (having a wrist pin directly connected to its body) with an independently expansible head portion yieldingly connected to said wrist pin.

Other objects and advantages will readily appear from the following description.

The invention consists, therefore, in the several novel features of construction, arrangement and combination of parts herein-after fully set forth and claimed.

The invention is clearly illustrated in the accompanying drawing, in which:

Figure 1 is a central, vertical section of a simple form of piston embodying the present invention; Fig. 2 is a side elevation of a certain member for connecting the head with the wrist pin; Fig. 3 is a horizontal section taken on the line 3—3 of Fig. 1; and Fig. 4 is a detail, vertical section of fragments of the cylindrical piston wall and head, showing the latter in expanded condition.

Referring to said drawing, the reference numeral, 10, designates a cylindrical wall open at both ends, and, 15, the disk-like piston head, which covers one end of said cylindrical wall, but is of less diameter than the cylindrical wall. As in the piston forming the subject matter of the prior applica-

tion referred to, the upper annular edge, 14, of the cylindrical wall, 10, is beveled off to form a tapered seat, and said piston head, 15, has a tapered or beveled edge portion, 16, that seats upon said beveled edge, 14, of the cylindrical wall, 10. The head is held upon its tapered seat by the mechanism which forms the subject of the present invention, and will be described herebelow.

The cylindrical wall, 10, of the piston, is directly connected to the connecting rod, 20, of the engine by a wrist pin, 19, said wrist pin being mounted in hollow bosses, 27, formed on, and projecting inwardly from, the cylindrical wall, 10. The wrist pin extends through a bearing aperture in the connecting rod, as is customary in pistons.

For connecting the piston head, 15, and wrist pin, 19, I employ a yoke shaped connecting member, 13, which has a cross piece, 24, and two downwardly projecting members, 12, that straddle the end of the connecting rod and have alined apertures, 28, formed near their lower ends for the reception of the wrist pin, 19. In the center of the cross piece, 24, of the connecting member, 13, is formed an aperture, 29, through which extends a stem, 17, formed on and projecting down from the piston head, 15, into the interior of the hollow piston body. A coiled compression spring, 25, is employed for holding the head, 15, on its seat, said spring being confined under compression between the lower side of the cross piece, 24, of the connecting member, 13, and a flange or shouldered portion, 23, formed on a sleeve, 22, that surrounds the stem, 17, and bears against a U-shaped washer, 21, the legs of which straddle a reduced neck portion, 29a, of the stem, 17, and seat in the groove around said reduced portion. The coiled compression spring, 25, bears downward against the flange or shoulder of the sleeve, 22, and acts to hold the piston head upon its seat on the cylindrical wall, 10. Preferably, the U-shaped washer fits in a recess, 30, formed in the lower face of the sleeve, so as to economize space; it is attached to the stem by pressing the sleeve upward against the spring until its lower face is flush with the top of the groove around the neck portion of the stem, and then slipping said U-washer upon said neck portion. When released, the spring forces the sleeve down upon the washer. The sleeve and

washer form a shoulder or abutment fixedly connected to the stem, for the spring to bear against and thereby hold the head on its seat.

5 In use, the head is free to expand radially, and independently of the cylindrical wall, 10, and in expanding said head rides up the tapered seat, 14, its stem and attached sleeve compressing the spring slightly. While the 10 head cools, it contracts and rides down the tapered seat, the spring expanding slightly during said movement of the head; consequently, the head and cylindrical wall are constantly kept in close contact, thereby preventing passage of gases between the head and cylindrical wall.

Slight variations of the details of construction shown and described, are possible, without departing from the spirit of this 20 invention, and I desire, therefore, not to limit myself to the exact form of the invention shown and described, but intend in the following claims to point out all of the invention disclosed herein.

25 I claim as new and desire to secure by Letters Patent:

1. A piston for motors, comprising a hollow piston body having an annular seat on one end, a wrist pin secured in said body, 30 and adapted for attachment to a connecting rod, an independently expandable piston head of less diameter than said body, seated upon said annular seat, and connections between said wrist pin and head for holding 35 said head on its seat.

2. A piston for motors, comprising a hollow piston body, a wrist pin secured directly thereto and adapted for connection with a connecting rod, an independently expandable 40 piston head of less diameter than said piston body, and yielding connections between said wrist pin and head.

3. A piston for motors, comprising a hollow piston body, a wrist pin secured directly 45 thereto and adapted for connection with a connecting rod, an independent, expandable piston head of less diameter than said piston body, and having a stem projecting into the hollow of said piston body, a connecting 50 member secured to said wrist pin, and a coiled, compression spring confined under compression between said connecting

member and a shoulder carried by said stem, said spring being arranged to hold said head upon its seat.

4. A piston for motors, comprising a hollow, open ended piston body, a wrist pin secured directly thereto and adapted for connection with a connecting rod, an independent, expandable piston head of less diameter than said piston body, seated upon one end of said piston body and having a stem projecting into the hollow of said piston body, a yoke shaped, connecting member having apertured members for the reception 65 of said wrist pin, and a coiled compression spring confined under compression between said connecting member and a shoulder on said stem, said spring acting to hold said head on its seat.

5. A piston for motors, comprising a hollow piston body, open at both ends, and having an annular tapered seat on one end, a wrist pin secured to said piston body and adapted for connection with a connecting 75 rod, an independently expandable, disk-like piston head of less diameter than the piston body, having a tapered edge portion seating on said tapered seat of the piston body, said head having a stem projecting into the hollow of said body, a yoke-like connecting member secured upon said wrist pin, a shouldered sleeve secured upon said stem, and a coiled compression spring, confined under compression between said yoke-like 85 connecting member and shoulder of the sleeve, and acting to hold said head upon its seat.

6. A piston for motors, comprising a cylindrical wall open at both ends, and having a tapered, annular seat on one end, and inwardly projecting hollow bosses intermediate its ends, a wrist pin mounted in said bosses and adapted for connection with a connecting rod, a piston head of less diameter than said wall and having a tapered edge portion seating on said tapered edge of the cylindrical wall, said head being expandable and contractible independently of the wall, and connections between said piston and 100 wrist pin, for yieldingly holding said head on said seat.

GEORGE ROBERT RICH.
